UNITED STATES PATENT OFFICE.

CORNELIUS S. MORRIS, OF ROCK ISLAND, ILLINOIS.

RECORDING APPARATUS FOR SCALES.

1,191,718.

Specification of Letters Patent. Patented July 18, 1916.

Application filed August 24, 1915. Serial No. 47,063.

To all whom it may concern:

Be it known that I, CORMELIUS S. MORRIS, a citizen of the United States, residing at Rock Island, in the county of Rock Island and State of Illinois, have invented certain new and useful Improvements in Recording Apparatus for Scales; and I hereby declare that the following is a full, clear, and exact description thereof, reference being 10 had to the accompanying drawings, which form part of this specification.

The present invention relates to printing apparatus for scales of automatic platform type and consists in the combinations and 15 arrangements of elements hereinafter described and particularly set forth in the accompanying claims.

The invention has for its purpose to provide an apparatus adapted for ready attachment to the housing of the scales in front of the indicator thereof whereby the amounts weighted, the tare, and other data may be printed on tickets at the time of the 20 actual weighing operations, and without 25 interference with the operation of the scales.

The invention further contemplates the use of the apparatus on the scales having the dial or drum type of indicator for computing purposes, and is especially adapted 30 for the kind of scales disclosed in my co-pending application for the United States patent bearing the Serial No. 47062 and dated August 24th, 1915.

The apparatus is shown by way of illustration in the accompanying drawings wherein:

Figure 1 is a front elevational view thereof. Fig. 2 is a top plan view of the same. Fig. 3 is an enlarged longitudinal sectional view, of the carriage and ticket holder. Fig. 4 is a transverse sectional view of the carriage, taken on the line 4—4 of Fig. 3, and showing the printing device *per se*. Fig. 5 is a similar view taken on the line 45 5—5 of Fig. 3. Fig. 6 is a detailed view of a section of the type bar, and Fig. 7 is a view of the ticket.

Referring to the construction in detail and wherein like reference characters indicate corresponding parts in the different views shown, 1 designates the casing of the scales, and 2 the housing or hood for the quadrant or segmental indicator 3 whose 50 graduations are arranged into three parallel sections 4, 5 and 6 adapted to be read in

succession. The indicators or pointers 7, 8 and 9 are of relatively different lengths to correspond with their respective scale sections 4, 5 and 6, after the manner described in my co-pending application above referred to. 60

The printing apparatus consists of a bar mounted on the casing 1 at its respective ends 10 11 and curved concentric with the indicator dial to form a track 12, and a radial flange 13. A carriage 14 is mounted to travel on the track 12 and is held thereon by embracing the flange 13 in the manner shown in Fig. 4, and having overlapping straps 15 engaging with said track 12. A 70 rack bar 16 is mounted on and suitably secured to the track 12 and is adapted to hold the carriage in different set positions through the means of a pawl 17 having a hand manipulating end 18, and a spring 19 75 engages said pawl and the arm 20 for holding the pawl under tension. A pair of rollers 21, suitably journaled in the carriage, travel on the track and act to hold the carriage in position for easy movement and 80 prevent jamming of the parts.

A series of type bars 22 *i. e.*, one for each indicator section is formed on, or otherwise secured to, the flange 13 and has its characters corresponding with the respective 85 character designations of said indicator sections whereby the indications of the amounts weighed may be printed on the ticket carried by the carriage. Said tickets are adapted to be contained, or individually 90 placed into the holder 23 that is mounted to have limited sliding movement on the top plate 24 of the carriage 14 (see Fig. 3). The holder 23 has ticket retaining flanges 95 25 and is also formed with a guard flange 26 that prevents the ticket from rubbing against the raised type portions of the bars 22, as seen from Fig. 4. A plurality of plungers 27 are mounted to work through the ticket holder to impress the tickets 100 against the type bars, and each of said plungers consists of a slotted portion 28 pivotally connected at 28^a to a head 29 that moves within the cylinder 30 when said plunger is depressed. The pivotal connection (28^a) between the plunger parts, 28 and 29, allows of sufficient movement of the plunger face to assure full surface contact of the type character against the ticket. 105

The several plungers are adapted to be 110

selectively operated in accordance with the positions of the indicator arms, and the means therefore consist of a lever fulcrumed on a suitable support 32 that is swiveled on 5 the carriage 14, and said lever has a pointed end 33 adapted to enter into a correspondingly shaped head 34 on the plunger rods 35 extending from the heads 29. A spring 36 surrounds each bar 35 and acts to restore 10 its respective plunger to normal position after the same has been depressed by the lever 31.

The ticket holder is adapted to be moved independently of the carriage in order to 15 bring the proper place on the ticket into position for printing, as will be further explained, and to this end said ticket holder is formed with a flange 37 formed on its under side with a rack 38 that meshes with 20 a pinion 39 journaled on the top plate 24 of the carriage and said pinion is manipulated by a knurled head 40 on the pinion shaft 41, (see Figs. 1 and 3). The upper surface of the flange 37 is formed with four 25 notches 42 adapted to be engaged by a tensioned detent 43 to hold the ticket holder in any one of the positions indicated by the marks, on the top plate 24. Said marks designate respectively the tare, the gross, 30 and the gross of the special weights (to wit three thousand pounds and six thousand pounds) indicated through the openings 44 and 45 in the casing 1.

In operation the proper pointer of the 35 arm 14^a is brought to register with the position of the scale indicator (7, 8 or 9) and the lever 31 is then moved to depress the proper plunger for printing the indicated amount on the ticket T, but before the 40 pointer of the carriage is brought to this position said carriage is first moved to that figure on the scale designating the tare and this amount is then printed in the proper column of the ticket by shifting the ticket holder to such position. It will sometimes be necessary to move the 45 pointer of the carriage a little to one side of the indicator as for instance when the indicator is nearer to thirty pounds than to the twenty pound mark, and in this instance it would be necessary to bring the pointer of the carriage directly over the figure 30 for printing this amount. It will be understood that the pointer of the carriage, and the figure of the scale must be brought into alinement with the type character before a printing operation can be 50 performed.

The ticket (see Fig. 6) has three columns 60 A, B and C corresponding respectively to the top, middle and bottom divisions of the scale, and a division E for the tare, the gross for ordinary weighing, and the gross designations to be used when the three 65 thousand and six thousand weights are re-

quired. This arrangement however, is purely arbitrary and inasmuch as it could be easily departed from an extended description of its use need not be given.

It is obvious that those skilled in the art 70 may vary the details of construction and arrangement of parts without departing from the spirit of my invention, and therefore I do not wish to be limited to such features except as may be required by 75 the claims.

Having thus described my invention what I claim as new and desire to protect by United States Letters Patent is:

1. The combination in a scales having a 80 quadrant indicator of a printing apparatus therefor comprising a quadrant track mounted concentric with the indicator, a type bar mounted parallel with said track, a carriage mounted on rollers to travel on 85 said track, a rack bar mounted on the track, a ticket holder movably mounted on the carriage, means for moving the ticket holder independently of the carriage, and means carried by said carriage for impressing the 90 tickets against the type bar, substantially as described.

2. The combination in a scales having a quadrant indicator of a printing apparatus therefor comprising a track mounted concentric with the indicator, a type bar having a plurality of rows of type mounted parallel with said track, a carriage mounted to travel on the track, a ticket holder mounted on the carriage, means for moving the 100 ticket holder in different positions for printing the tickets, and selective means mounted on the carriage for impressing the tickets against the type bar, substantially as described. 105

3. The combination in a scales having a quadrant indicator arranged in parallel divisions, of a printing apparatus therefor comprising a carriage movable parallel with said indicator, a type bar having a 110 plurality of rows of type, a ticket holder mounted on said carriage, pointers for said indicator divisions mounted on said carriage and means for impressing the tickets against the type bar, substantially as described. 115

4. The combination in a scales having a quadrant indicator arranged in parallel divisions, of a printing apparatus therefor comprising a carriage movable parallel with said indicator, a type bar having a plurality of rows of type, pointers for said indicator divisions mounted on the carriage, a ticket holder mounted on said carriage, means for moving the ticket holder into positions for printing the tickets, and selective means 120 mounted on the carriage for impressing the tickets against the type bar, substantially as described. 125

5. The combination in a scales having a quadrant indicator arranged in parallel di- 130

- visions, of a printing apparatus therefor comprising a carriage movable parallel with said indicator, a type bar having a plurality of rows of type, pointers for said indicator divisions mounted on the carriage, a ticket holder mounted on said carriage, means for moving the ticket holder into different positions for printing the tickets, a plurality of plungers associated respectively with the positions to which the tickets may be moved, and means mounted on the carriage for selectively actuating the plungers to print the tickets, substantially as described.
6. The combination in a scales having a quadrant indicator arranged in parallel divisions, of a printing apparatus therefor comprising a carriage movable parallel with said indicator, a type bar having a plurality 0 of rows of type, pointers for said indicator divisions mounted on the carriage, a ticket holder mounted on said carriage, means for moving the ticket holders into different positions for printing the tickets, a plurality of 5 plungers associated respectively with the positions to which the tickets may be moved, means for holding the ticket holders in set position, and a lever swiveled on the carriage for selectively actuating the plungers
- to print the tickets, substantially as de- 30 scribed.
7. The combination in a scales having a quadrant indicator arranged in parallel di- 35 visions, of a printing apparatus therefor comprising a flanged track, a carriage mounted to travel on said track and embrac- ing said flange, a type bar having a plurality of rows of type mounted on the track flange, a rack bar mounted on the track, pointers for the respective indicator divisions mount- 40 ed on the carriage, a pawl carried by the carriage to engage the rack and hold said carriage in set position, a ticket holder movably mounted on the carriage, means for moving the ticket holder into different po- 45 sitions for printing the tickets, means for holding said ticket holder in set position, and selective means mounted on the carriage for impressing the tickets against the type bar, substantially as described. 50

In testimony that I claim the foregoing as my own, I affix my signature in presence of two witnesses.

CORNELIUS S. MORRIS.
